UNITED STATES PATENT OFFICE.

WILLIAM E. McCOMB, OF CAMERON, MISSOURI.

FEED-WATER PURIFIER.

1,204,370.

Specification of Letters Patent. Patented Nov. 7, 1916.

Application filed November 5, 1915. Serial No. 59,795.

To all whom it may concern:

Be it known that I, WILLIAM E. McCOMB, a citizen of the United States, residing at Cameron, in the county of Clinton and State 5 of Missouri, have invented a new and useful Feed-Water Purifier, of which the following is a specification.

This invention has reference to feed water purifiers and its object is to provide a means 10 for purifying the feed water and separating oil or other ingredients and sediment liable to produce scale.

In accordance with the present invention the feed water pipe is provided with a by-pass 15 and appropriate valves with the by-pass having therein a suitable container so that the feed water passing through the by-pass may be made to traverse purifying agents before reaching the boiler. In the 20 main feed water pipe there is included an oil separator about which there is arranged a by-pass with suitable valves. The oil separator is so constructed that the water passing through it travels so slowly and by such 25 a tortuous path that the oil has ample time to separate from the water and impurities which might pass on to the boiler if carried by a fast flowing stream, have time to settle without liability of being stirred up by the 30 feed water traveling to the boiler.

The arrangement is such that either the purifier or the oil separator may be used independent of the other or the two may be used together, so that the feed water may 35 be both purified by suitable treatment and have any oil carried along with it separated from it before the water enters the boiler.

The purifying part of the device is shown, described and claimed in my application No. 40 873,843, filed Nov. 24, 1914, for means for dissolving and supplying boiler compounds to boilers, and hence in this application no claim is made to the specific construction of the purifying means in itself, but only in 45 conjunction with the oil separator.

The invention will be best understood from a consideration of the following detailed description, taken in connection with the accompanying drawings forming part 50 of this specification, with the further under-

standing that while the drawings show a practical form of the invention, the latter is not confined to any strict conformity with the showing of the drawings, but may be changed and modified so long as such 55 changes and modifications come within the scope of the appended claims.

In the drawings:—Figure 1 is an elevation with parts in vertical section showing the combined purifier and oil separator. 60 Fig. 2 is a section on the line 2—2 of Fig. 1, distant parts being omitted.

Referring to the drawings there is shown a pipe 1 which may be considered as connected at one end to the feed water pump 65 or injector of the boiler. The pipe 1 terminates at a T connection 2, from which there is a continuation 3 terminating at another T connection 4 and including a cut-off valve 5, which, like other valves to be described, 70 may be of the familiar globe type, or of any other suitable type. Leading from the neck side of the T 2 is another pipe 6 including a cut-off valve 7 and a check valve 8 on the side of the valve 7 remote from the 75 T 2. The pipe 6 terminates in a T 9, to the neck of which there is connected a cut-off valve 10, and extending from the valve 10 is a pipe 11 connected to the valve 10 by a short exteriorly threaded coupling 12. The 80 pipe 11 extends through an opening 13 in one head 14 of a cylinder 15, the opening 13 being closed by a plate 16 secured to the head 14 and traversed by the coupling 13. The cylinder 15 has its other end closed by a head 17 traversed by a short coupling 18 carrying branched pipes 19 within the cylinder, said pipes being connected by suitable 85 fittings and opening into the cylinder near their lower ends, the cylinder being upright 90 in its normal working position. The pipe 11 rises in the cylinder to a point near the upper end of said cylinder, while the pipes 19 open into the cylinder at a point near the bottom of the cylinder, but spaced sufficiently 95 from the lower head 14 to accommodate a mass 20 of purifying compound which may consist of soda ash, caustic soda and graphite, or any other material or materials employed in connection with boilers

for dissolving deposits and for other purposes. The cylinder 15 has its upper head 17 provided with a removable closing plug 21. Connected to the coupling 18 is a pipe 22 including a cut-off valve 23 and entering one end of a cylindrical chamber 24, the other end of which is connected by a pipe 25 to a T 26. Extending from one end of the T 26 is a pipe 27 including a cut-off valve 28 and connected to the neck of the T 4. The other end of the T 26 has connected to it a pipe 29 including a cut-off valve 30 and opening to the atmosphere or into some means of disposal. Leading from the T 9 15 on the opposite side thereof connected to the pipe 7 is another pipe 31 including a cut-off valve 32 and opening to the atmosphere. Branched off from the pipe 31 is a pipe 33 including a cut-off valve 34, and opening 20 into the cylinder 15 near the lower end of said cylinder.

Connected to and rising from the T 4 is a pipe 35 which may be in line with and which constitutes a continuation of the pipes 1 and 25 3. The pipe 35 includes a T 36 and a cut-off valve 37 on the side of the T 36 remote from the T 4. The pipe 35 has a continuation 38 entering an upright cylinder 39 by way of a passage 40 in the bottom head 41 of the cylinder 39. The passage 40 is closed by means 30 of a cap plate 42 secured in any appropriate manner to the head 41. Connected to the cap plate 42 is a drain pipe 43 including a cut-off valve 44.

35 The pipe 38 rises to and opens into the cylinder 39 at a high point quite close to the upper head of the cylinder shown at 45. At a high point in the cylinder 39 there is provided an outlet pipe 46 including a cut-off valve 47 and this cylinder is also provided with a gage glass 48 of customary construction.

Extending through the head 45 is a coupling 49 carrying a laterally spread series of 45 depending pipes 50 by means of a cross coupling 51. The pipes 50 are of a length to extend to a point near the bottom of the cylinder 39 and are there freely open, the pipe 38 being freely open at the upper end and 50 terminating quite close to the coupling 51 and within the range of indication of the gage glass 48. Connected to the coupling 49 is a pipe 52 in turn connected to a cut-off valve 53, and the latter is connected to a T 55 coupling 54 from which leads a pipe 55 which is assumed to be continued to the boiler. Branched off from the coupling 54 is a by-pass 56 including a cut off valve 57 and at the other end terminating at and connected to the T coupling 36.

If it be desired to purify the feed water the valve 5 is closed and the valves 7, 10, 23, 28, 37 and 53 are opened. The valves 32, 33, 30, 44, 47 and 57 are closed. Now, consider-

ing that there is a supply 20 of a suitable compound within the cylinder 15, the feed water finds its way from the pipe 1 through the pipe 11 into the cylinder 15 and flows into said cylinder by overflowing the upper end of the pipe 11. The water being affected more or less by the compound 20 finds its way through the pipes 19 to the chamber 24 and thence by way of the pipe 27 to the pipe 35, rising through the pipe 38 into the cylinder 39. When the cylinder 39 has 75 become sufficiently filled, the water finds its way out through the pipes 50 and ultimately through the pipe 55 to the boiler. Besides being treated to the action of the compound 20, the water on reaching the cylinder 39, 80 which may be of relatively large size as compared with the cylinder 15 and its chamber 24, is then in so large a container that its movements through the container are very sluggish, and since there are several out-flow pipes 50 in multiple, the movement of the water into the outlet pipes is correspondingly sluggish. This gives ample time for lubricating oil if present to separate from the water and rise to the surface thereof. 90 Such relatively long time is needed, since the oil is customarily in an emulsified condition when it enters the cylinder 39. Such cylinder or chamber 39 has the function of a settling and separating chamber permitting the oil to separate from the water and accumulate on top thereof, while any heavy impurities fall to the bottom of the cylinder. However, the entering water is so far from the bottom of the cylinder and the water stream so sluggish as it approaches the bottom of the cylinder that deposits remain 95 there undisturbed. By the arrangement described the feed water is purified by the action of the compound and any oil found in 100 the feed water is separated therefrom in the separating and settling chamber 39.

If it is not desired to use the purifying compound the valves 7 and 28 are closed and the valve 5 is open, the other parts remaining as before, so that any oil or impurities carried by the feed water into the cylinder 39 are removed from the feed water before it reaches the boiler.

By a suitable manipulation of the valves, 115 as by the closing of the valves 37 and 53 and the opening of the valve 57, the feed water is shunted around the cylinder 39 and so may pass directly from the feed water pump to the boiler. Or, the valve 5 may be closed 120 and the valves 7 and 28 opened with the valve 37 closed as before, and the feed water, suitably subjected to the purifying compound, may then pass to the boiler without going through the settling and oil separating 125 chamber 39.

The invention therefore provides a means for the purification of boiler feed water and

the separation from such water of lubricating oil and other materials liable to give trouble in the boiler and the purification and oil separation may take place continuously 5 in order, while the water is being fed to the boiler, or either arrangement may be used without the other.

By providing a multiple outlet near the lower end of the cylinder 39 with a single 10 high inlet there is no tendency to produce an inrush of water or the production of distinct streams, since the outlet is well separated from the inlet and of multiplied capacity over the inlet within the cylinder.

15 The by-pass pipe 56 permits the passage of water to the boiler when the oil separator is not needed. Furthermore, when cleaning out the cylinder 39 an air cushion may be formed in the by-pass and also in the separator by closing the valves 53 and 57, this being found advantageous during the cleansing 20 operation of the cylinder 39.

It is to be noted that there are four outlet pipes 50 in the cylinder 39, it having been 25 found in practice to be advisable to break up the outgoing stream into as many units as practicable to thereby prevent any tendency of any well defined down stream of water from the inlet to the outlet. Where several 30 outlets are provided this tendency is eliminated and there is no danger of the water taking a single course productive of a current, which will carry a certain amount of oil with it, since the oil on entering the cylinder or chamber 39 is usually in the 35 emulsified form and must have time to separate from the water to prevent going over with the water to the boiler.

With the present invention and with the 40 cylinder or chamber 39 five or more feet in length the water takes from 30 to 40 minutes to settle down from the upper end of the pipe 38 to the lower ends of the pipes 50. This is ample for the separation of the oil 45 and the settling to the bottom of the separator of any impurities reaching it. The oil accumulating on top of the water is readily drawn off through the pipe 46 and impurities are readily blown out through the 50 pipe 43.

In the purifier side of the invention the pipes 29 and 32 serve as blow off pipes for cleansing purposes while the pipe 33 provides a means for agitating the compound 55 20 when desired.

What is claimed is:—

1. A feed water purifier comprising a main pipe for receiving the water to be purified, a casing into which the water pipe enters to and discharges at a high point, an outlet for the casing communicating with the interior thereof at a low point and having multiple branches to slow up the flow of water from the high point of inlet to the

low point of outlet within the casing, another pipe branched about the casing from the inlet to the outlet pipes thereof, another casing, a branch pipe from the main pipe entering the second casing and discharging thereinto at a high point, multiple pipe outlets leading from low points of the second casing and connected together and to the main pipe, and valves in the pipes for cutting the casings into and out of connection with the main pipe and for utilizing the casings singly or in series at the will of an operator.

2. In feed water purifying means, a supply pipe and an oil separator included therein and comprising a chamber with the main pipe entering the chamber and discharging thereinto at a high point, and a plurality of outlet pipes in the chamber for connection to the boiler, said outlet pipes communicating with the chamber at a low point therein and representing a cross-sectional area a plurality of times that of the main pipe.

3. In a means for purifying feed water, a casing, a pipe entering the casing and discharging thereinto at a high point of the casing, and a series of pipes in surrounding relation to the first-named pipe and communicating with the interior of the casing at a low point therein, said series of pipes having a common outlet, whereby water entering the casing through the inlet pipe is discharged thereinto at a high point and flows in a plurality of directions away from the inlet pipe to the entering ends of the surrounding series of pipes.

4. In a means for purifying feed water, a casing, a pipe entering the casing and discharging thereinto at a high point of the casing, and a series of pipes in surrounding relation to the first-named pipe and communicating with the interior of the casing at a low point therein, said series of pipes having a common outlet, whereby water entering the casing through the inlet pipe is discharged thereinto at a high point and flows in a plurality of directions away from the inlet pipe to the entering ends of the surrounding series of pipes, said casing being provided with a by-pass pipe extending from the inlet and outlet pipes around the casing and the inlet, outlet and by-pass pipes each having a valve therein for the control of the flow of water through the pipes.

5. In a feed water purifier, an oil separator comprising a casing, a feed water pipe entering the casing and opening therein at a high point of the casing, another feed water pipe leading from the casing with a series of branch pipes within the casing in surrounding relation to the first-named pipe and opening into the casing at a low point

thereof, a branch pipe connecting the inlet and outlet pipes around the casing, a valve in the inlet pipe between the branch pipe and the casing, another valve in the outlet pipe between the branch pipe and the casing, and a valve in the branch pipe.

In testimony that I claim the foregoing as

my own, I have hereto affixed my signature in the presence of two witnesses.

WILLIAM E. McCOMB.
